United States Patent Office.

PATRICK J. McELROY, OF CAMBRIDGE, MASSACHUSETTS.

Letters Patent No. 79,487, dated June 30, 1868.

IMPROVED MEDICINE-DROPPER.

The Schedule referred to in these Letters Patent and making part of the same.

TO ALL WHOM IT MAY CONCERN:

Be it known that I, PATRICK J. McELROY, of Cambridge, in the county of Middlesex, and State of Massachusetts, have invented an Improved Medicine-Dropper; and I do hereby declare that the following, taken in connection with the drawings which accompany and form part of this specification, is a description of my invention sufficient to enable those skilled in the art to practise it.

In taking or administering liquid medicine, to be measured in drops, it is well known that it is very difficult and often impossible to drop the medicine with accuracy, on account of unsteadiness of the hand or unskillfulness, and the object of my invention is to remedy this trouble, by the construction and employment of a self-dropping device, which takes up the liquid from the bottle and drops it slowly and accurately in distinct and uniform drops.

My invention consists in a tube, (preferably made of glass,) to be attached to the bottle-cork or stopper, this tube being closed at top and contracted at bottom, and having a minute air-hole through its side near the top.

The drawings represent a drop-tube embodying my improvement.

A shows the tube within a bottle.

B, a view of it removed from the bottle.

a denotes the bottle, containing medicine or other liquid, b. c is the neck of the bottle, and d the cork or stopper. e denotes the drop-containing and delivering-tube, having its upper end inserted or driven into the bottom of the stopper, as seen at A.

The glass tube is preferably made hermetically close at top, though an open-top tube may be used, said top being closed by the covering portion of the stopper.

The tube is made of thin glass, or with a large bore, in proportion to its diameter, and at its lower end the glass is drawn down, so as to leave but a very small discharge-orifice, f, and near the top of the tube, or so as to come just below the cork, or above the liquid contents of the bottle, when nearly filled, is a very small air-inlet, g.

The tube being so made and applied to a stopper, when the tube and stopper are inserted in a vial containing liquid, the liquid will rise to the same height in the tube as in the vial, the fluid entering orifice f, (as by pressure it drives air from orifice g,) and in this condition of things the mouth of the vial is securely closed by the stopper, precisely as if the "drop"-tube were not employed.

When the medicine is to be taken, the stopper is drawn from the bottle, and with it the tube e, which, being held over a spoon or cup, the liquid will exude from the orifice f, in drops, and the dropping may be arrested, when desirable, or regulated, by placing the end of a finger over the air-inlet g.

By this means medicine or other liquid may be taken from a bottle in drops, by unsteady hands, and without skill.

I claim a tube, for dropping medicine or other liquid, constructed substantially as and for the purpose described.

PATRICK J. McELROY.
